CONVEYER FOR SOLDERING MACHINES

Otto. Wisner, Lowell, Mich., assignor to Lowell Specialty Company, Lowell, Mich., a corporation of Michigan

Application September 21, 1945, Serial No. 617,768

4 Claims. (Cl. 198—19)

1

This invention pertains to a machine which is particularly adapted for use in the manufacture of hand operated sprayers for distributing liquid disinfectants, insecticides, etc., although it should be understood at the outset that the principles of my invention may be embodied in machines of materially different types utilized in the manufacture of various articles.

In the production of sprayers comprising a hand operated reciprocating pump mounted on a receptacle in which the liquid to be distributed is stored and from which receptacle the liquid is discharged and atomized by the injector action of air blown across the upper end of a tube projecting downwardly into the liquid, it is essential that no air leakage from the pump cylinder into the receptacle occur, as such leakage would cause the discharge from the receptacle of more liquid than the pump would be capable of atomizing. Therefore, in the production of these sprayers it is essential that the side seam of the pump cylinder where it lies upon and is attached to the liquid receptacle be hermetically sealed to preclude such leakage from the cylinder into the receptacle. One of the purposes of my present invention is to provide a novel and improved machine for sealing such seam by soldering or, as it is sometimes termed, "floating" said seam.

Another purpose of my invention is to provide a machine which will automatically carry the pump cylinders to be soldered past the various stations where they are fluxed, soldered, wiped and cooled, and move such cylinders in succession into cooperative relation with the various bath tanks or other treating apparatus.

Another feature of my invention resides in the structure of the jigs or holders by which the pump cylinders are held and maintained in predetermined position during their travel in the machine, and in the devices cooperating therewith whereby the position of the pumps is changed as they pass the various operating stations and whereby they are released from the holders at the completion of their travel through the machine.

Another purpose of my invention is to present the pump cylinders in convenient position for the manual application thereto of the tubes through which the liquid is discharged from the receptacles, the machine being adapted to hold the cylinders in a convenient position for the application of the tubes and the attachment of the same thereto by a soldering operation without interrupting the progress of the cylinders through the machine.

Other purposes are to provide a machine which would be simple in construction, economical to manufacture, easy to service, and which will be efficient and reliable in operation.

Other objects and advantages will be apparent as the same becomes better understood by refer-

2

ence to the following description when considered in connection with the accompanying drawings, illustrating an embodiment of the principles of my invention which at the present time seems preferable for illustrative purposes.

Referring to the drawings,

Fig. 1 is a plan view of the machine;

Fig. 2 is an end view of a pump cylinder for the production of which my machine is adapted;

Fig. 3 is a fragmentary sectional view of such pump cylinder taken on the line 3—3 of Fig. 2;

Fig. 4 is an elevation of one side of my machine viewed in the direction of the arrow 4 in Fig. 1;

Fig. 5 is a similar view of another side viewed in the direction of the arrow 5 in Fig. 1;

Fig. 6 is a similar elevation looking at an end of the machine as viewed in the direction of the arrow 6 of Fig. 1;

Fig. 7 is an enlarged fragmental sectional view on the line 7—7 of Fig. 5;

Fig. 8 is a similar view on the line 8—8 of Fig. 6;

Fig. 9 is a sectional view on the line 9—9 of Fig. 4; and

Fig. 10 is a sectional view on the line 10—10 of Fig. 8.

Referring to the drawings more in detail, it will be observed that the machine is triangular in contour, comprising upper and lower triangular frames 11 and 12, respectively connected by posts 13 and supported at a convenient height above the floor upon suitable standards 14.

The frame is provided near its top at the corners with sprocket wheels 15, 16, and 17, respectively around which an endless double chain 18 is trained. Sprocket wheels 15 and 16 are idlers, but sprocket 17 is mounted upon a drive shaft 19 which is driven through suitable transmission 21 from an electric motor 22. The chain is driven in a counterclockwise direction viewing Fig. 1.

At regularly spaced intervals the chain is equipped with brackets 23 upon the depending arms 24 of each of which there is pivoted on pin 25 a holder for the work piece to be operated upon, which in the present instance is the shell or cylinder of a reciprocating hand operated spray pump designated generally on the drawings by reference character 26. From Figs. 2, 3, 8 and 9 it will be apparent that the shell is shaped to provide the pump cylinder portion 27 and the spray chamber portion 28, the portions being separated by a transverse wall 29 having an air discharge port 31 from the pump cylinder. An end closure 32 having a large central opening 33

55 for the discharge of the spray is double seamed or otherwise secured to the end of the shell. The shell body, which is made from a flat sheet of tinplate or other suitable metal, has the edges of the sheet joined to form the cylindrical shell by lock-seaming the edges together to provide the longitudinal seam 34. Before the shell is mount-

ed on the liquid containing receptacle of the sprayer, a liquid discharge tube 35 is secured to the partition wall 29 with its delivery end disposed in the path of air from the air discharge opening 31 from the pump cylinder, so that the air discharged through this opening will by an injector or eduction action draw the liquid from the receptacle upwardly through the tube 35 and cause it to be discharged and dispersed by the air stream into a spray. The tube 35 is secured in proper position to each wall 29 by a drop of solder 36 while the shell is presented and held in predetermined position by the machine, as will be later described.

It will be observed that the tube 35 extends through an opening 37 in the wall of the chamber 28. The tube also projects through an opening in the wall of the receptacle over which the shell is disposed, the shell being soldered or otherwise securely attached to the receptacle in a well known manner.

Since considerable pressure is developed in the pump cylinder by the operation of the pump piston, and since the side seam 34 is apt to be loosened or partially opened at and near the juncture of the cylinder 27 with the larger chamber 28, leakage of air under pressure from the pump cylinder through this seam and into the liquid receptacle is apt to occur and, if it does, the pressure created in the receptacle renders the operation of the sprayer very unsatisfactory, as such pressure increases the liquid delivery through the tube 35 so that a stream of liquid, instead of the desired spray, is discharged from the device. One of the functions of the machine embodying my present invention is to seal the side seam of the shell in the vicinity of the partition wall 29 by soldering the lock seam, thereby precluding leakage from the pump cylinder through this seam. For the purpose of holding and manipulating the shell for the application of the solder thereto, and to subsequently present it in convenient position for the mounting of the discharge tube 35 therein, each shell is mounted in a holder previously mentioned as being pivotally supported from depending arm 24 on bracket 23 attached to the chain 18.

Each holder comprises a head 38 pivoted on a pin 25 from arm 24 of a bracket 23 and equipped with one or more anti-friction cam engaging rollers 39. A supporting frame structure depending from each head 38 comprises preferably a pair of bars 41 and 42 adjustably connected together by bolts 43 projecting through slots in one or more of the bars, so that the length of the frame structure thereby provided may be adjusted to accommodate the machine to shells of different lengths. The lower end of the bar 42 is bent or projected outwardly at right angles to provide a portion 44 upon which a guide block 45 is secured by a bolt 46 or by other suitable means. The guide block 45 is of a size and shape to be received with a reasonable degree of snugness within the lower end of the cylindrical shell 26 of the sprayer barrel, thereby to center and position the barrel or shell to prevent its displacement or wabbling.

A holder or clamp consisting of a fixed and a yielding jaw is mounted upon each of the frame bars 41 and extends outwardly above the bottom 44. From Figs. 8 and 10, particularly, it will be seen that a stationary jaw 47 is welded or otherwise fixed to the outer face of bar 41 and is shaped to provide a curved socket for the reception of a shell 26. The arm 48 of the jaw, which

extends outwardly beyond a shell when in position, has pivotally mounted thereon at 49 a yieldable clamping jaw 51, which is provided with a notch 52 to accommodate the side seam 34 of the shell, and is urged into clamping position, as shown in Fig. 10, by a coiled expansion spring 53 interposed between the tail of the jaw and a bracket 54 carried by the arm 48. It will be obvious that the shell may be positioned in this holding jaw by moving it laterally between the jaws 47 and 51, and that the angular position of the shell to present the side seam outwardly is assured by making certain that such seam is positioned in the notch 52 of the jaw 51. In placing a shell in the holder the open lower end is first placed over the guide block 45, whereupon the shell is tilted to upright position with the side seam in extreme outward position to be engaged in notch 52. The tilting of the shell to vertical position forces it between the stationary jaws 47 and the yieldable jaw 51, by which it will be clamped and held in position so that the desired operations can be performed thereon.

The loading of the machine or, in other words, the placing of the shells in the holders, is done by an operator stationed near the righthand end of the short side of the machine, that is, in the vicinity of the sprocket wheel 16 of the machine as seen in Fig. 1. At this point the holders are held in substantially vertical position by a cam or guide rod 55 (Figs. 6 and 8) extending horizontally of the machine in position to engage the rear face of the holder frame and thereby maintain said frame and the shell mounted therein in substantially vertical position.

When the thus loaded holder passes the sprocket wheel 16, the rollers 39 of the holder are brought into engagement with a cam bar 56 (Fig. 4) by which the holder, having passed the guide bar 55, is tilted on its pivot into substantially horizontal position. A short distance beyond the sprocket wheel 16 a flux tank 57 (Figs. 4 and 9) is carried by suitable supports 58 beneath the path of travel of the shells. The cam bar 56, however, is so shaped that as each shell reaches a position above the flux tank its outer end is tilted downwardly, as illustrated in Fig. 9, from the dotted line position to the full line position of said figure, whereby that portion of the side seam in the vicinity of the bulge forming the spray chamber portion 28, is submerged in the flux. The cam bar 56 is so shaped as to permit the shell to resume a horizontal position to clear the upper edge of the flux container and the upper edge of a solder bath 59. The solder in bath 59 is maintained in liquid condition by the flames of gas burners which are supplied in a manner well known from a gas supply pipe 61. Here again the shape of the cam bar 56 is such that the holder is tilted to submerge the outer lower portion of the shell in the solder for the purpose of closing and sealing the side seam 34 of the shell in the vicinity of the partition wall 29.

The shell, after leaving the solder bath, is subjected to a wiping action to remove any surplus solder, this wiping being done by a rotary brush 62, driven in any suitable manner as, for instance, from an electric motor 63 through a suitable power transmitting belt 64. After being wiped, the shell is then submerged in a cooling bath 65 to set the solder, whereupon the holder passes beyond the extremity of the cam rod 56. Control of the position of the shell is thereupon assumed by a guide rod 66, which extends around the apex of the triangular frame and along the opposite

side of said frame, as will be apparent from Figs. 4, 5 and 7.

As the shells travel in succession along the side of the machine shown in Fig. 5, they are retained substantially in the position shown in Fig. 7, which is convenient for the operator seated at this side of the machine to insert into each shell and solder in position one of the delivery tubes 35 as the shell is traveling along. In actual practice, two operators are seated at this station to speed up the production by mounting the delivery tubes in the shells in the manner indicated. These operators work upon alternate shells as they travel along this side of the machine.

As the shells pass around the corner frame where the sprocket wheel 15 is located, an unloading bar 67, disposed in a horizontal position (Figs. 5 and 6) but making an acute angle with the adjacent portion of the path of travel of the conveyor, engages the upper portion of the shells at their sides adjacent to the conveyor and gently releases them from the clamping jaws of the holder. This is done by simply pressing the shells outwardly, and, in order that injury to the lithographing on the shells may not result, the bar 67 is preferably made of suitable plastic which is smooth and non-abrasive in character. To assist in the release of the shells from the clamping jaws, I have provided, as illustrated in Fig. 6, a bar 73 pivoted to the frame at 74 and provided at one end with a cam surface 75 formed by a loop in the wire which is disposed in the path of the anti-friction rollers 39, by which the bar 73 is tilted in a counter-clockwise direction as the rollers of the successive shell holders progressively pass the cam surface. The other end of the bar is bent to provide an inclined portion 76 shaped to cooperate with the releasing bar 67 in withdrawing the shells from the clamping jaws at the proper position. As the shells are released from the holder they drop in succession into a chute 68 (Fig. 5) from which they are delivered onto a conveyor 69 and thereby transferred to the next assembly station.

From Fig. 6 it will be observed that sections of each of the upper and lower frame members 11 and 12 are respectively joined by connecting members 71 and 72 which have adjustable connection with the frame members through bolt and slot connection 73'. The adjustability thus provided enables the frame to be expanded to place the chain 18 under proper tension and provide for take-up necessitated by wear.

It should be apparent from the foregoing that I have provided a machine which automatically applies solder to the side seam where required, and which presents the shells in proper position for the application thereto of the delivery tubes by operators seated alongside the machine. The machine is simple in construction, occupies a minimum of floor space, can be economically produced, and is efficient and reliable in operation.

The structural details illustrated and described may obviously be varied within considerable limits without exceeding the scope of my invention as defined in the following claims.

I claim:

1. In a machine of the character described including an endless conveyor adapted to travel in a substantially horizontal plane, means for actuating said conveyor, depending brackets carried by the conveyor in spaced apart relation and a plurality of holders each pivotally mounted on the depending end of a bracket for supporting shells each having an exterior projection, each

holder comprising a portion for engagement with an end of each shell positioned therein to center and accurately position the shell, a stationary jaw carried by the holder in spaced relation to said holder portion and a spring pressed jaw pivoted relative to said stationary jaw, one of said jaws being notched to engage an exterior projection of a shell and retain the shell in predetermined position on the holder.

- 10 2. In a machine of the character described including a conveyor and a plurality of shell holders mounted thereon for supporting similar shells each of which has a positioning shoulder in a predetermined position, each holder including a supporting frame having a depending adjustable part provided with a centering device at its base for engaging with an end portion of a shell, a stationary jaw, a movable jaw pivotally mounted with respect to the stationary jaw, one 15 of the jaws having a notch adapted to engage the shell shoulder thereby to position the shell, and a spring acting on said movable jaw to bias the same into shell-holding relation with said stationary jaw.
- 15 3. In a machine of the character described having an endless chain conveyor and means for driving the same, a plurality of shell holders pivotally mounted on said conveyor in spaced apart relation, each holder comprising a pair of jaws 20 arranged to hold a shell in fixed position on the holder, means including stationary cams and cam followers mounted adjacent to the holders whereby said holders are moved into predetermined position with respect to the chain at successive 25 positions, and means including a stationary bar and a pivotally mounted bar for releasing shells from successive holders at a predetermined position.
- 25 4. In a machine of the character described, the combination of a triangular frame, an endless chain supported by said frame and adapted to travel in a substantially horizontal plane, one of the sides of said frame being adjustable as to length whereby the tension on said chain may be 30 regulated, a series of shell holders pivotally mounted on said chain in spaced apart relation, stationary cams in the path of said holders for tilting the holders on the chain to dispose them in predetermined positions at various operating stations along their path, and means including a stationary bar and a pivoted bar for releasing shells from successive holders as they reach a 35 predetermined position.

OTTO WISNER.
